ATTORNEYS.

UNITED STATES PATENT OFFICE

ALBERT E. HUTT, OF NEW ROCHELLE, NEW YORK

DISPENSING NOZZLE

Application filed April 15, 1930. Serial No. 444,392.

My invention consists of a novel construction of a dispensing nozzle for effecting the conveying of compressed air or other fluid to a desired point by means of a handle or body member, a fixed pipe therein, a slideable plunger mounted on said pipe and having a transverse flange adapted to effect the actuation of the valvular elements, said plunger being suitably packed and under tension with respect to said fixed pipe whereby pressure or movement of the handle in one direction will open the valvular elements, and releasing or cessation of the handle pressure will automatically effect the closure of the valvular elements.

16 consists of a novel construction of
a ¹⁷ slideable plunger having a terminal conical
seat, adapted to coact with the closed ported
end of a fixed pipe mounted in a suitable han-
¹⁸ dle or body.

It further consists of a novel means for concealing and protecting the end of the fixed pipe member aforesaid.

It further consists of other novel features
25 of construction and advantage, all as will be
hereinafter pointed out in the specification
and claims appended hereto.

and claims appended hereto.

It further consists of a novel dispensing nozzle wherein the shut off is effected at the 30 extreme end of the discharge orifice, thus preventing any drip or wastage of the dispensed fluid after the nozzle has been closed.

For the purpose of illustrating my invention, I have shown in the accompanying drawing one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

45 Referring to the drawing in which:—

Figure 1 represents a side elevation of a novel dispensing nozzle, embodying my invention.

Figure 2 represents on an enlarged scale a longitudinal section on line 2-2 of Figure 1,

showing the valvular member in closed position.

Figure 3 represents a fragmentary sectional view similar to the left hand portion of Figure 2 showing the valvular member in open position. 55

Figure 4 represents a longitudinal sectional view of another embodiment of my invention.

Similar numerals of reference indicate corresponding parts. In carrying out my invention, I employ a tubular cylindrical body or handle member 1 having a rear inlet chamber 2, which is threaded at 3 for the attachment of a suitable hose 4, which is locked in position with respect to the handle member 1 by the nuts 5 and 6 seen in Figure 1. 7 designates a spring chamber or plunger chamber within the handle member 1, which is separated from the rear inlet chamber 2 by the parti- 70

tion 8, said spring chamber having the vent or port 9 opening thereinto from the atmosphere. 10 designates a fixed inner pipe or stationary tube whose rear end is tightly fitted or fast in the partition 8 and is secured therein by the washer 11 and the nut 12. 13 designates a slideable plunger which is fitted with-

lates a plunger 13, which is fitted with in the chamber 7, so as to be readily reciprocated therein, the rear end of said plunger being provided with a packing 14 and a packing retainer 15 contiguous to the spring 16, one end of which latter bears against said packing.

retainer 15 while its other end bears against the contiguous wall of the partition 8 as will be understood from Figure 2. The fixed inner pipe or tube 10 has its front end closed as indicated at 17 and is provided with the outwardly flared terminal conical wall 18 having a port 19 therein, said flared terminal wall 18 being seated in the conical seat 20 in the front end 23 of the nozzle by reason of the tension of the spring 16 when the parts are in the position seen in Figure 2. 21 designates a flange extending transversely to the slidible plunger 13 and preferably integral therewith

and normally positioned with respect to the end 22 of the handle member 1, substantially as seen in Figure 2 when the port 19 is closed, the spring 16 serving automatically to hold the slidable plunger 13 with respect to the 132

fixed inner pipe 10 normally substantially as seen in Figure 2. When it is desired to convey fluid to the desired point as to a transmission, it is only necessary to insert the forward end 5 of the nozzle into the opening of said transmission until the flange 21 contacts with the wall of said transmission and to push the handle member 1 forwardly whereupon the parts will assume the position seen in Figure 10 3, the port 19 being open and fluid under pressure being discharged from the hose 4 through the fixed pipe 10 and port 19 to the desired point. Upon removing the flange 21 from the wall of the transmission or releasing 15 slightly the grip or grasp upon the handle 1, the parts move from the position seen in Figure 3 to the position seen in Figure 2 by reason of the tension of the spring 16 the contact of the walls 18 and 20 limiting the extent of forward movement of the plunger 13 as is evident. In the construction seen in Figure 4, I have shown a slightly modified form of device for protecting the end of the fixed pipe wherein the fixed pipe is indicated as 24 20 and is provided with the flared end 25 closed by the relatively thick wall 26 and provided with a port 27. The flared end 25 is normally seated against the conical wall 28 of the plunger 33 as seen in Figure 4 and the closed end 26 reciprocates and is protected in the chamber 29 which is provided with the main exit port 30 and the vent port 31. The vent port 31 is preferably positioned in a cap member 32, which is in threaded engagement 25 with the front end of the plunger member 33, which is provided with a flange 21 of the same character and function as seen in Figures 1 to 3.

It will be understood that the right hand portion of Figure 4 is constructed similar to the right hand portion of Figure 2, in respect of the threaded portion 3, the partition 8, vent 9, packing 14, and nut 12, so that when the flange 21 seen in Figure 4 is pressed 40 against the wall of the chamber into which it is desired to introduce fluid, the port 27 will align with the port 30 and fluid can flow from the hose 4 through the fixed pipe 24 and ports 27 and 30 to the desired point. 45 The vent 9 permits the escape of air when the spring 16 is compressed, and the vent 31 similarly functions when the plunger 33 is actuated with respect to the fixed pipe 24.

I am aware that the invention may be embodied in other specific forms without departing from the spirit or essential attributes thereof, and I therefore desire the present embodiment to be considered in all respects as illustrative and not restrictive, reference 50 being had to the appended claims rather than to the foregoing description to indicate the scope of the invention.

Having thus described my invention, what I claim as new and desire to secure by Letters Patent, is:—

1. In a device of the character stated, a handle member, having a rear inlet chamber adapted for a hose attachment, a front plunger chamber, a partition separating said chambers, a pipe fixed in said partition, open at its rear end and closed at its front end and provided with an outwardly flaring, conical, terminal portion having a port therein, a plunger carried by said handle and slidable longitudinally upon said fixed pipe, and having a front terminal conical seat conforming to the front contour of said fixed pipe, a flange on the front of said plunger, and a spring intermediate said partition and the rear of said plunger. 70

2. In a device of the character stated, a handle member, having a rear inlet chamber adapted for a hose attachment, a front plunger chamber, a partition separating said chambers, a pipe fixed in said partition, open at its rear end and closed at its front end and provided with an outwardly flaring, conical, terminal portion having a port therein, a plunger carried by said handle and slidable longitudinally upon said fixed pipe, and having a front terminal conical seat conforming to the front contour of said fixed pipe, a flange on the front of said plunger, and a spring intermediate said partition and the rear of said plunger, and an apertured cap for said plunger covering and protecting the end of said fixed pipe. 75
